UNITED STATES PATENT OFFICE.

ERNEST F. KOEHLER, OF MARLBORO, MASSACHUSETTS.

DESIGN FOR A BONNET FOR MINERS' SAFETY-LAMPS.

46,403.

Specification for Design.

Patented Sept. 15, 1914.

Application filed July 17, 1914. Serial No. 851,650. Term of patent 7 years.

To all whom it may concern:

Be it known that I, ERNEST F. KOEHLER, a subject of the Emperor of Germany, residing at Marlboro, in the county of Middlesex and State of Massachusetts, have invented a new, original, and ornamental Design for Bonnets for Miners' Safety-Lamps, of which the following is a specification, reference being had to the accompanying drawing, forming part thereof.

Figure 1 is a plan of the bonnet for a miner's safety lamp and Fig. 2 is a side elevation showing my new design.

I claim:

The ornamental design for a bonnet for miners' safety lamps, as shown.

ERNEST F. KOEHLER.
